Invantor,
Chris Heskett,
By Joseph A. Mintern
Attorney

UNITED STATES PATENT OFFICE.

CHRIS HESKETT, OF INDIANAPOLIS, INDIANA.

NONPREHEATING OIL BURNER.

Application filed September 23, 1920. Serial No. 412,233.

To all whom it may concern:

Be it known that I, CHRIS HESKETT, a citizen of the United States, residing at Indianapolis, in the county of Marion and ⁵ State of Indiana, have invented new and useful Improvements in Nonpreheating Oil Burners, of which the following is a specification.

This invention relates to improvements in ¹⁰ oil burners wherein the hydrocarbon vapors are generated without preheating the oil and are fed through the mixer and discharged under a pressure of air that simulates the action and effect of a blow-torch. The object ¹⁵ of the invention is to produce a concentrated intense heat which is easily and quickly started and easily controlled, and which is applicable to heating rivets for structural iron and steel work, and for melting ²⁰ Babbitt metal, brass and other metals, and to a variety of work.

I accomplish the objects of the invention by the mechanism illustrated in the accompanying drawing, in which—

²⁵ Fig. 1, is a side elevation and partial section of my invention and appurtenances. Fig. 2 is a section of the generator and mixer on a large scale and Fig. 3, is a section of the oil supply pipe showing the strainer.

Like characters of reference indicate like parts in the several views of the drawing.

A body-member 4, here shown as of cast brass and approximately three inches long, ³⁵ has a longitudinal central bore 5, one fourth inch in diameter extending two thirds of its length and thence to the end reduced to five thirty seconds of an inch. Into the threaded end of bore 5 a pipe 6 is screwed and the pipe communicates with the top or air-end of a combined air and oil tank 7. The tank is only partially filled with a fuel-oil and the air above it is maintained under pressure by any suitable means so that both the oil and ⁴⁰ air from the tank are supplied under pressure.

The body 4 has a diagonal branch 8, through which is a one fourth inch bore 9, which communicates with bore 5 near where ⁴⁵ the latter is reduced as shown in Fig. 2. The outer end of the bore 9 is threaded and into it a plug 10, is screwed. A longitudinal central bore one sixty-fourth of an inch in diameter extends longitudinally through plug 10, and on a projecting threaded end of the plug a pipe 11 is screwed. This pipe is con-

tinued to the top of the tank 7 and passes through the top and is continued down nearly to the bottom of the tank to keep the air from entering it at various levels at ⁶⁰ which the oil will stand under use. A strainer 12 is assembled in the pipe 11, and a control of the flow of oil through the pipe is secured by the globe valve 13 and a needle valve 14, the latter being located within convenient reach of an operator standing by the body 4. A similar needle valve 15 is placed in the pipe 6, also within convenient reach of the operator.

A fire-pot formed of a sheet-metal housing ⁷⁰ 16, supported on suitable legs 17, and lined with fire-brick 18, is here shown in one embodiment of my invention for heating rivets and by the placing of a crucible within the fire-pot metals of various kinds may be melted. In the form shown, a bracket 19, extends from the housing 16 to the body 4, as a support for the latter. It also supports a pipe 20 which is two inches in diameter in the form shown. This pipe is held at the proper distance from the adjacent end of body 4 and in axial alinement therewith to form a mixer for the admission of atmospheric air to complete the combustion of the mixture which passes into the fire-box through pipe ⁷⁵ 20, through the housing 16 and lining 18, as shown, and the mixture is lighted within the fire-box.

A portable torch may be made by supporting the pipe 20 from body 4 and making the pipes 6 and 11 flexible.

In the operation of my device compressed air from tank 7 is discharged through the reduced opening in the head 4, carrying with it a fine stream or spray of oil supplied from the tank through pipe 11 and reduced by passing through the small opening of plug 11 acting as a nozzle. The chambers 5 and 9 are preliminary mixing chambers so that the mixture of air and oil issues in a nebulized form from the reduced bore of body 4, and passes through the pipe 20, drawing with it atmospheric air in requisite quantity to support complete combustion of the mixture discharged from pipe 20 into the fire-box.

I do not desire to limit my invention to the dimensions given nor to the specific details described, but what I do claim as new and wish to secure by Letters Patent, is—

1. In an oil burner, a body-member having a gas passage the cross-sectional area of

2
the major portion of which is more than twice that of its discharge end, a branch member from the body having a bore of approximately the same diameter as the major portion of the bore of the body-member and opening into said major bore near its reduced portion, a round plug in the outer end of the bore of the branch member having a bore of less cross-sectional area than that of the reduced portion of the body member, means for supplying air under pressure to the bore of the body member and oil under pressure to the bore of the branch, and a tube separated from the body member by an air-space through which the mixture issuing from the body-member is discharged.

10 2. In an oil burner, a member having a

passage connected with a compressed air supply discharging through an opening of less cross-sectional area than that of the air-supply connection and having a branch passage connected with an oil supply under pressure, said branch having an oil passage smaller than that through said discharge end, needle valves in said air and oil connections, and a pipe with a bore larger than any of the passages of said member through which the mixture issuing from the member discharges, said pipe being separated from said discharging member by an air space. 20 25 30

Signed at Indianapolis, Indiana, this the 11th day of September 1920.

CHRIS HESKETT.
